CLAIM

The ornamental design for a folding wagon, as shown and described.

DESCRIPTION

FIG. 1 is a front, top perspective view of a folding wagon, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front elevation view thereof, shown in an alternative position;

FIG. 10 is a left side elevation view thereof;

FIG. 11 is an enlarged view of detail "11" identified in FIG. 1;

FIG. 12 is an enlarged view of detail "12" identified in FIG. 1;

FIG. 13 is an enlarged view of detail "13" identified in FIG. 1;

FIG. 14 is an enlarged view of detail "14" identified in FIG. 2;

FIG. 15 is an enlarged view of detail "15" identified in FIG. 2;

FIG. 16 is an enlarged view of detail "16" identified in FIG. 2; and,

FIG. 17 is an enlarged view of detail "17" identified in FIG. 5.

The dashed lines in the figures illustrate portions of the folding wagon that form no part of the claimed design. The dash dot dash lines in FIGS. 1, 2, 5, 11, 12, 13, 14, 15, 16 and 17 are for the purpose of illustrating the enlarged views indicators and form no part of the claimed design.
